D. K. Winder

Force Pump

No 16,669.

Patented Feb 17, 1857.

UNITED STATES PATENT OFFICE.

DANL. K. WINDER, OF CINCINNATI, OHIO.

METHOD OF RAISING WATER.

Specification of Letters Patent No. 16,669, dated February 17, 1857.

To all whom it may concern:

Be it known that I, DANIEL K. WINDER, of Cincinnati, Hamilton county, Ohio, have invented a new and useful Apparatus for 5 Raising Water; and I hereby declare the following to be a full, clear, and exact description thereof, reference being had to the annexed drawing, making a part of this specification, wherein my device is represented by a longitudinal section.

The object of my invention is to provide a cheap, easily operated and effective means of raising water from a cistern in either large or small quantities at pleasure.

15 (a) is a cistern from whose cover (b) a post or staff (c) depends vertically into the cistern. To this post near its lower end is attached a vessel called by me the "reservoir" formed with two concentric cylinders 20 (d) (e) having their annular interval (f) closed at top and bottom. The central space within the inner cylinder is open at top but at bottom is provided with a floor (g) having a valve aperture (h) opening upward. Near the lower end of the inner cylinder (e) is a valve aperture (i) opening from the central space into the annular space 25 of the reservoir.

Formed to slide up and down snugly but 30 freely within the central space of the reservoir is a cylindrical vessel (j) called by me the "plunger." This plunger and the inclosing central space of the reservoir are not ground or otherwise expensively fitted 35 to each other but approach with sufficient closeness for the thin film of water to form a joint. The plunger (j) is closed at the top and bottom its floor having a valve aperture (k) opening upward.

40 Made fast to the top of the plunger and extending vertically downward to near its floor, and upward to a convenient height above the cistern cover is a pipe (l) terminating at top in a spout (m) and handle (n). Projecting also through the top of the plunger (j) to near its floor, is a similar pipe (o) whose upper end extending a short distance above the top of the plunger is connected by a flexible tube (p) with the 45 lower part of the annular chamber, the communication at the lower end being completed by a short pipe (q) to which the lower end of the tube (p) is secured. This pipe (q) is ordinarily closed by a stop cock 50 (r) which may shut automatically by a

weight on its handle or otherwise. From the handle of this cock a rod or cord (s) extends upward above the cistern cover where it terminates in a ring or handle (t) by which to lift the cord and by that means 60 open the cock when desired.

Projecting laterally from one side of the plunger is an arm (u) which, being forked, straddles the post (c) and impinging against a pin (v) the plunger is thereby prevented 65 from escaping out of the central space.

Before immersion in the water both reservoir and plunger are full of air but when immersed, portions of water rising through the described valves into these vessels crowd 70 their contained air into the upper parts until the expansive force of the air within balances the weight of the hydrostatic column without.

More than one suspending post may be 75 employed, if desired.

The operation is as follows: When water is desired by the bucket-full the tube (l) and plunger (j) are depressed by the hand or foot of the operator, compelling the water 80 contained in the central space to enter the plunger and the annular chamber of the reservoir in two separate portions. Of these portions, that which enters the plunger being opposed by the reaction of its contained 85 air is driven up the tube (l) and escapes through the spout (m); the foot being then withdrawn the plunger rises to its uppermost position, and its contained air resumes 90 its former dimensions. Meanwhile the valve (i) closing, that part of the water which was forced into the reservoir, is there retained under pressure of the confined air for future or present use being especially 95 serviceable and intended for small and frequent supplies. If for example it be desired to fill a tumbler merely; the object may be attained without waste of water or superfluous effort by the operator, the exertion being only that of opening the cock 100 (r) for an instant, by lifting the ring (t), which results in the escape from the annular chamber of the desired volume of water which, passing through the flexible tube (p) into the plunger (j) disturbs the equilibrium 105 there and causes a similar volume of water to issue through the exit tube (l) and spout (m).

By the mode of management described, with an experimental machine used in my 110

cistern, the reserve chamber is found constantly effective for all quantities less than a bucket-full.

The entire absence of any machine-fitted 5 and closely-packed working joints, enables the apparatus to be cheap in its construction and not liable to derangement.

What I claim herein as new and of my invention is:—

10 The arrangement and combination sub-

stantially as described; of annular reservoir (*f*) with the plunger (*j*), tube (*l*), flexible pipe (*p*), valves (*h*) (*i*) (*k*) and cock (*r*) for the purposes explained.

In testimony of which invention I here- 15 unto set my hand.

D. K. WINDER.
